UNITED STATES PATENT OFFICE.

EDOUARD LABELLE, OF MONTREAL, QUEBEC, CANADA.

HYDROCARBON BURNER.

Application filed January 24, 1927. Serial No. 163,245.

This invention relates to new and useful improvements in hydrocarbon burners and the object of the invention is to provide a simple and efficient device which will thoroughly atomize the fuel before it enters the furnace so that complete combustion of the fuel will be ensured.

Another object is to provide a burner of the class stated which will be very easily dismantled for cleaning and repairs.

A further object is to provide a burner of the class stated which will assist the oil in its passage towards the discharge end or nozzle of the burner by heating the fuel and assisting the flow thereof.

In the drawings which show one embodiment of my invention, I provide a passageway for crude oil in the form of a tube surrounded by an annular passageway for steam or such like fluid which is supplied to the burner under pressure from a source not shown. The steam in its passage draws a quantity of the oil through perforations formed in the wall of the oil feed tube which is provided with a cap having a perforated flange through which the mixture passes to the final mixing chamber formed in the dome shaped nozzle. A recess or chamber is formed in the cap and means are provided to guide a small quantity of the mixture from the annular passageway directly into the final mixing chamber.

In the drawings:—

Figure 1 is a side sectional elevation showing my improved burner.

Figure 2 is an end sectional elevation taken on the line 2—2 Figure 1.

Figure 3 is an end sectional elevation taken on the line 3—3 Figure 1.

Figure 4 is an end sectional elevation taken on the line 4—4 Figure 1.

Referring more particularly to the drawings, 11 designates a T piece of special formation having two inlets 12 and 13 and two outlets 14 and 15, one positioned within the other. The outlet 14 is in direct communication with the inlet 12 while the outlet 15 communicates with the inlet 13. The outlet 14 is internally threaded to receive the end 16 of the pipe 17, which extends outwardly from said T piece toward a furnace (not shown). The outlet 15 is internally threaded to receive the end 18 of the pipe 19, the inner wall of which is spaced from the outer wall of the pipe 17 forming an annular passageway 20 surrounding the last

mentioned pipe. The end 21 of the pipe 17 is externally threaded to receive an internally threaded hollow sleeve 22 the walls of which have radially disposed perforations 23 formed therein. Surrounding said sleeve and having its inner wall spaced from the other wall of the sleeve is the nipple 24, one end of which is internally threaded to receive the end 25 of the pipe 19. The other end of the nipple is reduced to receive the open end of a dome shaped nozzle 26 having an outlet or slot 27 formed in its closed or dome shaped end 28. Screwed into or otherwise attached to the sleeve is the fuel pipe 70 cap 29 having an outwardly extending flange 30, having perforations 31 formed therein to allow fuel to pass directly from the preliminary mixing chamber 32 formed between the sleeve and the nipple, into the final mixing chamber 33 formed between the flange and the inner wall of the dome shaped nozzle. The outer edge of said flange contacts with the inner wall of the nozzle. Formed in the end of the cap is the recess 34, the open end of which is positioned in the final mixing chamber. Radially disposed holes 35 formed in the cap behind the flange form a communication or passageway between the preliminary mixing chamber and the recess 85 so that a small quantity of the mixture will flow into said recess and cause a circulation of the fluid within the recess and the final mixing chamber to further atomize the mixture before it passes through the slot to the 90 furnace.

In operation, crude oil is fed into the burner through the inlet 12 and the pipe 17. Air or steam under pressure is fed into the device through the inlet 13 and passes along 95 the annular chamber surrounding the fuel pipe. In my preferred form steam or pre-heated air to be fed into said chamber as the heat given out therefrom will tend to increase the flow of the oil and also assist in 100 raising its temperature so that it will be easily atomized. The flow of steam draws the oil through the apertures in the wall of the sleeve into the preliminary mixing chamber where a partial atomizing and mixing 105 takes place. The oil is then driven through the apertures in the flange of the cap into the final mixing chamber. A small quantity of the partially atomized mixture is driven through the apertures in the cap walls into 110 the recess formed therein. This flow through the wall of the cap being at right angles to

the main flow through the flange causes a circulating and mixing action in proximity to, within, and through the recess and the circulating fuel when submitted to the force of the incoming fluid causes complete atomization of the mixture which is sprayed into the furnace. The length of piping may be varied to suit existing conditions with regard to the furnace. Other modifications may be made without departing from the spirit of the invention. The burner as will be readily seen is very easy to dismantle for cleaning and repairs. By unscrewing the nozzle and the nipple the flanged cap is exposed and the cap and sleeve may be very easily dismantled for inspection or cleaning by unscrewing them from one another and from the end of the fuel feed pipe.

Having thus described my invention, what I claim is:—

1. A hydrocarbon burner comprising an oil supply pipe, an atomizing fluid supply pipe, a sleeve secured to the end of the oil supply pipe, a nipple secured to the end of the fluid supply pipe, a cap secured to the end of the sleeve, a dome shaped nozzle secured to the end of the nipple, and pro-

vided with a slotted outlet at its closed end, a flange carried by and extending at right angles to the longitudinal axis of the cap and spaced from the tip of the dome shaped nozzle to provide an intervening final mixing chamber, there being apertures formed in said flange to establish communication between said final mixing chamber and a preliminary mixing chamber reserved between the walls of the nipple and sleeve, said sleeve having radial perforations formed in the wall thereof to allow oil to flow therefrom into said preliminary mixing chamber, and a recess formed in the cap and having communication with both chambers to cause a slight agitation and mixing action between said chambers.

2. A burner according to claim 1, in which the communication between the recess and the preliminary mixing chamber comprises a plurality of apertures formed in the wall of the cap and positioned at right angles to the main fuel supply channels through the flange of the cap.

In witness whereof, I have hereunto set my hand.

EDOUARD LABELLE.
